UNITED STATES PATENT OFFICE

JACOB H. HIRSCH, OF CHICAGO, ILLINOIS, ASSIGNOR TO AUTOMATIC BURNER CORPORATION, OF CHICAGO, ILLINOIS, A CORPORATION OF ILLINOIS

PIPE-CLOSURE DEVICE

Application filed November 17, 1930. Serial No. 496,297.

My invention relates more particularly to closure devices for closing the upper threaded extremities of the filler-pipes of oil tanks buried in the ground and forming parts more particularly of oil-burner installations. These filler pipes in accordance with common practice extend at their upper filler openings above the ground a considerable distance, usually from six to eight inches, to avoid the possibility of water flowing into these pipes, these pipes in the case of house installations commonly being located in grass-plots and are capped by a plain cap protecting only the top thereof.

15 My object is to provide a closure device for the upwardly projecting end of such a filler-pipe having a portion surrounding said filler-pipe and depending from the zone of screw connection substantially to the ground line.

20 Referring to the accompanying drawing:

Figure 1 is a view in elevation of a closure device embodying my invention and showing it in position of use; and

25 Figure 2, a vertical sectional view of the structure of Fig. 1 the section being taken normal to the joint between the two sections forming the body of the closure device.

In the arrangement shown, the filler pipe of an oil-storage tank (not shown) is represented at 3, this pipe in practice rising from the oil tank which would be buried in the ground indicated at 4, and extending upwardly an appreciable distance, say about six or eight inches, above the level of the ground, 35 as for example a grass plot adjacent the house equipped with oil-burner apparatus supplied with oil from the tank, the upper extremity of the pipe 3 being shown as externally threaded as represented at 5.

40 In accordance with my invention I provide as a removable and replaceable closure for the upper end of the pipe 3, a closure device 6. The closure device 6 which may be provided of any suitable form to accomplish the purpose stated, is shown as in the form of a dog which, when applied to the pipe in closure position as shown in the drawing, extends close to, or against, the ground 4. To this end the closure device is of hollow form 50 with its lower end open to adapt it to be ap-

plied to the upper, open end of the pipe 3, and above the lower open end is internally threaded at 7 when to be used with a pipe threaded as above stated and in accordance with common practice to adapt it to be screwed upon 55 the threaded upper end 5 of the pipe the closure device being provided with a constricted portion or rib 8 in which the threads 7 are formed, the threads 7 in the closure device being preferably located above the lower open end of the device a distance substantially equal to the distance from the threaded portion 5 of the pipe to the ground-level, whereby the closure device extends at its lower end close to, or against, the ground. 60

65 Preferably the body of the closure device is cast and made in two sections the joint therebetween being represented at 9, these sections being secured together as by a screw 10 which extends through one of the two sections and screws into a threaded socket 11 in a lug 12 on the other section, the internal contour of the main portion of the body being substantially the same as the external contour of such part. 70

75 The sectional construction of the closure device together with the two means as at 5 and 10, to hold the sections in place on the pipe 3, is important especially since the device is always exposed to the elements, and if the threads at 5 should rust or "freeze", the fastening 10 could be removed or broken to enable separation of the sections and hence removal thereof without an unscrewing action. 80

85 While I have illustrated and described the closure device as presenting a particular form, or shape, it will be readily understood that it may be provided of any other unconventional form or shape without departing 90 from the spirit of my invention.

95 What I claim as new, and desire to secure by Letters Patent, is:

1. A closure device for the purpose set forth, formed of a hollow body consisting of 95 longitudinally divided sections, means separably securing the sections together, said body having an opening in its lower end at which the body is adapted to be applied to the threaded end of a pipe to be capped and 100

provided internally with threads which reach short of the lower end of said device and at which the device screws upon the threaded end of the pipe whereby the device 5 extends materially below the upper end of the pipe.

2. A closure device for the purpose set forth, formed of a hollow body consisting of longitudinally divided sections, means separably 10 securing the sections together, said body being open at its lower end at which the body is adapted to be applied to the threaded end of the pipe, said body having an internally threaded constricted portion disposed above, and spaced from, the lower end 15 of the body and at which the device screws upon the threaded end of the pipe, whereby the device extends materially below the upper end of the pipe, the closure device having 20 a special exterior configuration serving dually for ornamentation and to provide a gripping means to facilitate the application thereto and removal therefrom with respect to the filler pipe.

25 3. In combination with the upwardly extending threaded end portion of a filler-pipe for an oil tank positioned in the ground, a closure device for said end portion comprising a hollow body consisting of longitudinally 30 divided sections, means separably securing the sections together, said body containing an opening in its lower end at which the body is adapted to be applied to the threaded end of the pipe and provided internally with 35 a threaded portion spaced from the lower extremity of said device and at which the device is screwed upon the upper threaded end of said pipe with the lower end of the device extending materially below said threaded 40 portion, the closure device having a special exterior configuration serving dually for ornamentation and to provide a gripping means to facilitate the application thereto and removal therefrom with respect to the 45 filler pipe.

4. In combination with the upwardly extending threaded portion of a filler-tube for a tank positioned in the ground, a closure device for said end portion consisting of a hollow body, comprising longitudinally divided 50 sections and open at its lower end whereby it may be applied over said end of the filler-tube, said sections having an inwardly extending rib reinforcing the same and also 55 provided with screw threads applied to the threaded end of the filler-tube, said device having a portion depending below said rib and substantially to the ground, and fastening means securing the sections of the device 60 together and located above said rib.

JACOB H. HIRSCH.
